(57) **CLAIM**

The ornamental design for a "lab coat," as shown and described.

DESCRIPTION

FIG. 1 is a right side front perspective view of a first embodiment of the lab coat showing my new design for a male; FIG. 2 is a front view of the lab coat of FIG. 1;

FIG. 3 is a left side view of the lab coat of FIG. 1; FIG. 4 is a rear view of the lab coat of FIG. 1; FIG. 5 is a right side view of the lab coat of FIG. 1; FIG. 6 is a top view of the lab coat of FIG. 1; FIG. 7 is a bottom view of the lab coat of FIG. 1; FIG. 8 is a front inside view (lab coat flipped open) of the lab coat of FIG. 1; FIG. 9 is a right side front perspective of a second embodiment of the lab coat showing my new design for a student; FIG. 10 is a front view of the lab coat of FIG. 9; FIG. 11 is a left side view of the lab coat of FIG. 9; FIG. 12 is a rear view of the lab coat of FIG. 9; FIG. 13 is a right side view of the lab coat of FIG. 9; FIG. 14 is a top view of the lab coat of FIG. 9; FIG. 15 is a bottom view of the lab coat of FIG. 9; FIG. 16 is a front inside view (lab coat flipped open) of the lab coat of FIG. 9; FIG. 17 is a right side front perspective of a third embodiment of the lab coat showing my new design for a female; FIG. 18 is a front view of the lab coat of FIG. 17; FIG. 19 is a left side view of the lab coat of FIG. 17; FIG. 20 is a rear view of the lab coat of FIG. 17; FIG. 21 is a right side view of the lab coat of FIG. 17; FIG. 22 is a top view of the lab coat of FIG. 17; and, FIG. 23 is a bottom view of the lab coat of FIG. 17; and, FIG. 24 is a front inside view (lab coat flipped open) of the lab coat of FIG. 17.

The broken lines showing a stethoscope, mobile phone, and pager in FIGS. 1, 9 and 17 are for illustrative purposes only and form no part of the claimed design. The remaining broken lines, shown throughout the views showing button details, pocket openings and stitching, represent the portions of the lab coat, which form no part of the claimed design.
